Sushi-maker pictured in "Design News", Mar. 25, 1985.

* cited by examiner

Primary Examiner — Stella M Reid*Assistant Examiner* — Elizabeth J Oswecki(74) *Attorney, Agent, or Firm* — SAIDMAN DesignLaw Group(57) **CLAIM**

The ornamental design for a sushi maker, as shown and described.

DESCRIPTION

FIG. 1 is a perspective view of a sushi maker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the sushi maker and form no part of the claimed design.
